UNITED STATES PATENT OFFICE.

ANDRO PISARCIK, OF VANDERGRIFT, PENNSYLVANIA, ASSIGNOR TO AMERICAN SHEET AND TIN PLATE COMPANY, OF PITTSBURGH, PENNSYLVANIA, A CORPORATION OF NEW JERSEY.

ROLLING-MILL GUIDE.

Application filed June 6, 1927. Serial No. 196,752.

This invention relates to improvements in guides for use on the delivery side of sheet and plate mills and more particularly for use on the delivery or "catcher's" side of sheet and plate roughing mills, and has for its object the provision of a novel form of guide and guide support whereby the guide will be supported entirely on the support and free of the rolls.

10 In the drawings—

Figure 1 is a sectional elevation through a stand of rolls having this invention applied thereto.

Figure 2 is a top plan of the guide rest-bar 15 and guides removed from the mill.

Figure 3 is an enlarged sectional elevation through the guide rest-bar and guide.

Referring more particularly to the drawings, the numeral 2 designates the rolling mill housings which are of the "two high" type and have rolls 3 journaled therein in the usual manner.

20 A guide plate 4 is mounted on the roller's or feed-in side of the mill over which the roller slides the sheets or plates when feeding them into the bite of the rolls 3.

On the delivery or catcher's side of the mill I have provided an angle shaped guide rest-bar 5 which extends horizontally between and is secured to the housings 2. The bar 5 is arranged with one flange 6 extending horizontally and with its other flange 7 extending vertically upwardly next to the rolls 3.

35 The bottom or horizontal flange 6 is provided with a pair of longitudinally extending slots 8 which are enlarged at their inner ends at 9 and are undercut along their longitudinal edges as at 10 for a purpose to be described.

A pair of sheet receiving guides A and B are mounted on the rest-bar 5 and each comprises a substantially wedge shaped body portion 12 having a transverse groove 13 therein, adapted to fit loosely over the flange 7 of the bar 5 so as to provide for a limited rocking movement of the guides relative to the bar 5. The body portions 12 are provided with a rearwardly projecting flange 14, adapted when the guides are positioned on the bar 5, to overlie the bottom flange 6 of the bar 5. The flanges 14 of the guides are apertured at 15 to receive bolts 16 which are mounted in the slots 8 in the bottom flange 6 of the bar 5.

The bolts 16 are adapted to be mounted in the slots 8 by passing their headed ends through the enlarged ends 9 of the slots 8 and said bolts are then moved along the slots 8 so that their heads will be engaged in the undercut portions 10 of the slots 8.

30 The bolts 16 extend upwardly through the slots 8 and through the apertures 15 in the flanges 14 of the guides A and B and have adjusting nuts 17 and 18 threaded thereon to lock the guides in position.

Coiled springs 19 are mounted around each of the bolts 16 between the flange 6 of the guide bar 5 and the flanges 14 of the guides and serve to form a resilient and yieldable support for the rear ends of the guides A and B.

35 The forward ends of the guides A and B are adapted to terminate just short of the surface of the lower mill roll 3 at a point slightly below its top surface so as to receive the sheets fed between the rolls and yet clear the rolls and thus prevent wearing of the guides and rolls.

When the rolls 3 are re-surfaced or new rolls are substituted having a different diameter than the rolls for which the guides A and B have been set, the guides may be readily reset or adjusted by simply unscrewing the nuts 17 and 18 which will permit the spring 19 to expand and rock the guides A and B about the flange 7 of the guide rest-bar 5, thereby tilting the guides toward and closer to the rolls 3.

40 If new rolls of a larger diameter than those originally in the housing are substituted for the worn rolls, it will be necessary to reverse the operation of the nuts 17 and 18, that is, screw down the nuts in order to compress the spring 19 and rock the guides A and B about the flange 7 of the guide rest-bar 5, thereby tilting the guides upwardly and away from the rolls 3.

In order to adjust the guides transversely for different sizes of sheets it is only necessary to loosen the nuts 17 and 18 and slide the guides A and B transversely along the rest-bar.

45 While I have shown and described one specific embodiment of my invention it will be understood that I do not wish to be limited thereto since various modifications may be made without departing from the scope of my invention as defined in the appended claims.

July 3, 1928.
